ASHTRAY

Fredrick Graffenberger, Milwaukee, Wis.

Application July 14, 1944, Serial No. 544,905

1 Claim. (Cl. 131—240)

1

This invention relates to ash trays.

One object of the present invention is to provide an improved ash tray for receiving lighted cigars and cigarettes of various lengths and to retain the same against accidental dislodgement from the tray.

Another object is to provide an ash tray by which the burning of a lighted cigar or cigarette may be controlled by the position in which the same is deposited in the tray.

Other more specific objects and advantages will hereinafter appear, expressed or implied, from the following description of an ash tray constructed in accordance with the present invention.

In the accompanying drawings:

Figure 1 is a plan view of an ash tray embodying the present invention.

Fig. 2 is a transverse sectional view thereof taken substantially along the line 2—2 of Fig. 1.

Fig. 3 is a transverse sectional view taken substantially along the line 3—3 of Fig. 1.

The ash tray selected for illustration comprises a bowl 10 having a peripheral wall 11 and an outwardly projecting rim 12. The rim 12 is fashioned to provide a series of V-shaped radial grooves 13 which preferably slope inwardly and intersect the inner wall surface of the bowl to form a series of notches 14 of sufficient width and depth to freely receive and position a cigar or cigarette lodged therein.

A series of upstanding lugs or posts 15, extending across the bottom of the bowl, project upwardly to a common level within the bowl. The lugs 15 are preferably diamond shaped in horizontal section with an obtuse side corner of each opposite a similar corner of an adjacent lug. These lugs are preferably upwardly tapered and at their upper ends these side corners of successive lugs are preferably equally spaced a distance slightly less than the diameter of a cigarette so as to receive and position a cigar or cigarette lodged in the recesses thus formed between the lugs. Both end lugs 15' of the series are preferably shorter than the others and preferably merge into the side wall of the bowl to better accommodate the end of a cigar or cigarette lodged thereon.

The series of lugs 15 thus provide a convenient and secure lodgement for the lighted end of a cigar or cigarette, while the notches 14 in the rim 12 provide a convenient and secure lodgement for the opposite end thereof.

With the opposite ends of each cigarette or cigar thus cradled at opposite ends, it is securely

2

retained against accidental dislodgement from the bowl. It will be noted that there is a wide variation in the distance between any of the notches 14 and any of the various positions of lodgement thus provided along the series of lugs 15, so that various lengths of cigarettes and cigars, from the partially consumed cigarette to the full length cigar, may be supported thereon without excessive projection beyond the bowl.

10 It will be further noted that with a cigarette positioned, as at *a* in Fig. 1, with its burning tip disposed well beyond the series of lugs 15, the cigarette will continue to burn freely; that with the cigarette in position *b* with its lighted tip 15 adjacent the series of lugs 15, the burning may be effectively checked by the cooling effect of the contacting lugs; and that the fire in the lighted tip may be effectively smothered and promptly extinguished by placing the cigarette in position 20 *c* with the lighted tip engaged between the bases of adjacent lugs 15. The burning of a lighted cigarette may thus be controlled by properly positioning it in the bowl.

Various changes may be made in the embodiment of the invention hereinabove specifically described without departing from or sacrificing the advantages of the invention as defined in the appended claim.

I claim:

30 An ash tray comprising a bowl having a circular series of grooves formed in the rim thereof, each of said grooves being adapted to receive and cradle an end portion of a cigar or cigarette lodged thereon, and a row of upstanding substantially diamond shaped lugs extending diametrically across the bottom of said bowl, the side corners of successive lugs being spaced apart to form recesses adapted to receive and cradle the opposite end portion of the cigar or cigarette in 40 any of the various angular positions the latter may assume relative to the row of lugs.

FREDRICK GRAFFENBERGER.
